TIRE TUBE TESTING DEVICE

Original Filed June 7, 1924

E. Q. Ruppert.

WITNESS:

P. Milner
INVENTOR
BY
Victor J. Evans
ATTORNEY

UNITED STATES PATENT OFFICE.

PLESANT MILNER, OF CROWLEY, LOUISIANA.

TIRE-TUBE-TESTING DEVICE.

Application filed June 7, 1924, Serial No. 718,628. Renewed August 20, 1928.

This invention relates to a holder for pneumatic tubes, the general object of the invention being to provide means for holding the tubes while they are being tested for holes and punctures, the device acting to limit the expansion of the tube by the compressed air in the same.

This invention also consists in certain other features of construction and in the combination and arrangement of the several parts, to be hereinafter fully described, illustrated in the accompanying drawings and specifically pointed out in the appended claims.

15 In describing my invention in detail, reference will be had to the accompanying drawings wherein like characters denote like or corresponding parts throughout the several views, and in which:—

20 Figure 1 is an elevation of the device.

Figure 2 is a transverse sectional view showing a tube in the same.

Figure 3 is a detail side view.

As is well known, it is extremely difficult 25 to discover small punctures in the pneumatic tubes as the tube will expand to such an extent when air is introduced into the same as to endanger the tube so that it is impossible to place sufficient air in a tube to discover 30 small punctures. It is the object of my invention to provide means for confining the tube and preventing undue expansion of the same when air is introduced into the same so that sufficient air can be introduced into the tube to cause some of the air to escape through 35 the puncture so that the puncture can be detected.

In carrying out my invention I provide a 40 ring-shaped member A for containing the tube, which is shown at B in Figure 2, under compression. This member is formed with perforations 1 and it is preferably composed of two sections 2 and 3 so that the tube can be easily placed in the same or removed therefrom. The section 3 is provided with the angle flanges 4 for receiving the beads 5 formed on the edges of the section 2. Cam latch members 6 are connected by the links 7 to ears 8 on the sections 2 and these latch 50 members are adapted to engage under the

flanges 4 of section 3 to hold the two sections together.

From the foregoing it will be seen that a tube can be placed in the device and the two sections clamped together and then the tube 55 can be inflated with an amount of air which is sufficient to cause some of the air to escape through the puncture and thus enable the puncture to be detected. The device will limit the expansion of the tube and thus prevent it from bursting under great pressure.

While I have shown the device as formed of perforated material it will of course be understood that it can be formed out of wire mesh or similar material.

It is thought from the foregoing description that the advantages and novel features of my invention will be readily apparent.

I desire it to be understood that I may make changes in the construction and in the 70 combination and arrangement of the several parts, provided that such changes fall within the scope of the appended claims.

What I claim is:—

1. A device of the class described including separable ring members each arcuate shaped in cross section and formed with perforations, an angular flange formed on each edge of one of said members, a bead on each edge of the other member adapted to rest 75 upon each flange, and clamping members carried by the last mentioned member for engagement beneath each flange on the first mentioned member to clamp said members together.

2. A device of the class described including separable ring members each arcuate shaped in cross section and formed with perforations, an angular flange formed on each edge of one of said members, a bead formed 80 on each edge of the other member adapted to rest upon each flange, spaced ears carried by the last mentioned member, links pivoted to said ears, and cam latch members carried by said links and adapted to engage beneath 85 each angular flange to clamp said ring members together.

In testimony whereof I affix my signature.

PLESANT MILNER.
